UNITED STATES PATENT OFFICE.

JAMES ALEXANDER FLANAGAN, OF TORONTO, ONTARIO, CANADA.

BOBBIN-WINDING MECHANISM FOR SEWING-MACHINES.

1,387,141.

Specification of Letters Patent. Patented Aug. 9, 1921.

Application filed February 4, 1920, Serial No. 356,202. Renewed June 1, 1921. Serial No. 474,300.

To all whom it may concern:

Be it known that I, JAMES ALEXANDER FLANAGAN, a British subject, residing at the city of Toronto, in the county of York and 5 Province of Ontario, Dominion of Canada, have invented certain new and useful Improvements in Bobbin-Winding Mechanism for Sewing-Machines; and I hereby declare the following to be a full, clear, and exact 10 description of the same.

My present invention relates to a bobbin winding attachment for sewing machines in which the bobbin spindle is mounted in a spring-pressed rocker arm, adapted to oscillate between an operative and an inoperative position; the object of the invention being to provide this attachment with a peculiarly constructed latch to engage said arm and hold it in operative relation with 15 the flywheel, and with a castoff member unitedly movable with the latch and extending into alinement with the thread receiving portion of the bobbin to be engaged by the thread when the bobbin is filling and to be 20 moved by the pressure exerted by the thread, as the winding proceeds to disengage the latch from the arm, and thereby enable it and its related parts to automatically move from the operative to the inoperative position. 25

In carrying out the invention the rocker arm is hinged to a supporting member or stationary bracket, preferably forming part of or secured to the wheel guard or to some 30 other stationary part of the machine, and is acted upon by a spring which tends to move it and hold it in the inoperative position. A 35 detent or latch is pivoted to the stationary bracket to engage the rocker arm and hold 40 it in the operative position against the tension of the spring, and this detent or latch is provided with a castoff member integrally formed or rigidly connected with it, the castoff member being arranged in alinement 45 with the thread receiving portion of the bobbin, so that the thread wound thereon will press against it and gradually move it as the winding proceeds to disengage the latch from the rocker arm.

For an understanding of the invention 50 reference is to be had to the following description and to the accompanying drawings, in which:

Figure 1, is a side elevational view of the flywheel, wheel guard and the bobbin winding mechanism, showing the detent or latch engaging the rocker arm and holding the friction wheel in contact with the flywheel, 55

Fig. 2, is a similar view to Fig. 1, showing the position of the parts when the detent 60 has released the rocker arm;

Fig. 3, is a top plan view of the parts in the same position as shown in Fig. 1,

Fig. 4, is a front elevational view of the parts in the same position as in Fig. 1, 65

Fig. 5, is a detail view of the rocker arm,

Fig. 6, is a detail view of the detent or latch, and

Fig. 7, is a detail view of the supporting member. 70

Like characters of reference refer to like parts throughout the specification and drawings.

a represents the usual flywheel of the sewing machine mounted on the shaft *b*, and *c* represents the usual wheel guard for the flywheel. At the side of the wheel guard *c* is a supporting member which is shown in the drawings to take the form of a bracket or arm *d*, inclined downwardly-forwardly 75 beyond the wheel guard *c*. This bracket or arm *d* is preferably secured to the wheel guard *a* by two bolts *e*, *e'*, the lower bolt *e'*, being the nearer one of the two to the periphery of the wheel guard *c*, and serving as 80 a pintle for the hub *f* of the detent *g* hereinafter described.

Near the outer end of the bracket or arm *d* is a screw threaded hole *h*, to receive the screw threaded shank of a stud *i*. Encircling the stud *i* is the cylindrical hub *j* of the rocker arm *k*, and within the hub *j* is a coiled spring *l*, one end *m* of which is anchored to the hub *j*, and the other end *m'* of which is extended beyond the coils and anchored between two pins *o* projecting from the adjacent side of the bracket or arm *d*. 95

This arrangement enables the spring to

press the rocker arm k in a direction outward from the flywheel, and move it to what may be termed its inoperative position.

At or near the free end of the rocker arm k are spaced bearings p , p' , and journaled in these bearings is the bobbin spindle q , on the outer end of which is fixed a friction wheel q' to engage with the flywheel a .

Mounted on the bobbin spindle q between the bearings p , p' , is a worm r of such proportions as to fill the space between these bearings and contact their opposed faces. This worm rotates with the bobbin shaft q and meshes with a worm wheel s , journaled 15 on a stud t , secured to the rocker arm k . On the worm wheel s is a cam u , which engages with an arm v of the thread distributor w .

At the junction of the thread distributor w and arm v is a lug x , and passing through the lug x is a stud y , which enters a cylindrical lug z , forming part of the rocker arm k . Within the cylindrical lug z is a coiled spring a' , one end of which is anchored 25 within the cylindrical lug z , and the other end of which is anchored to the thread distributor w , so as to maintain the arm v continually in contact with the periphery of the cam u .

During the revolution of the bobbin spindle q , the worm r meshing with the teeth of the worm wheel s , causes the revolution of the latter and the cam u . This cam is so timed as to gradually and slowly move the 35 thread distributor w in a direction toward the flywheel, and then when it has moved the distributor to its limit of motion in that direction to permit of the spring a' gradually moving the thread distributor to its limit of 40 motion in the opposite direction, the thread distributor thus passing across the face of the bobbin b' alternately in opposite directions at each revolution of the cam to distribute the thread evenly across the face of 45 the bobbin.

The bearing p is aligned with the detent g and is provided with a flattened surface p'' to be engaged by the detent. The detent as shown in the drawings overlies the top of 50 the arm and is formed with a hook shaped end f'' , which engages with the flattened surface p'' and holds the rocker arm in its operative position and maintains the friction wheel q' in contact with the flywheel a .

Extending from the hub f is a castoff arm g' , which overlies the thread receiving part of the bobbin b' when the bobbin is mounted on the bobbin spindle as shown in the drawings, the free end of the arm g' being curved upwardly to provide a clearance for the thread distributor w , when the parts are in the position shown in Figs. 1 and 4.

The detent g and the castoff arm g' are

in the same transverse plane and the flattened surface p'' of the bearing p is of such height as to permit of the arm g' entering between the flanges of the bobbin before the thread is wound thereon. As the bobbin fills during the winding operation the thread 70 comes into contact with and presses against the arm g' , and gradually moves it outward as the winding proceeds. This arm is preferably integral with the detent g and its hub f , and as the winding proceeds it unitedly 75 lifts with it the detent g , the lifting continuing until the thread reaches the periphery of the bobbin flanges.

At this point the arm g' and the detent are raised sufficiently to release the hook shaped end f'' of the detent from engagement with the bearing p . The spring l then moves the rocker arm forwardly to its inoperative position, and the friction wheel is then free from contact with the flywheel. 85

In its operative position the rocker arm k assumes a perpendicular or substantially perpendicular position with the friction wheel in contact with the flywheel a , and the detent g lying loosely on the top of the 90 bearing p and the hook shaped end f'' engaging the flattened surface p'' .

When the thread winding upon the bobbin raises the castoff arm g' and detent g sufficiently to disengage the hook shaped end f'' 95 from the bearing p , the rocker arm, under the influence of the spring l , turns on the stud i and the friction wheel moves outwardly and forwardly from the flywheel until the forward movement of the rocker arm is arrested 100 by the stop c' on the hub j engaging with the spring l .

A convenient method of forming this stop is to recess the cylindrical wall of the hub j , as shown in Fig. 5, the recess being of sufficient length to permit of the free movement of the hub during the rocking of the arm. 105

Having thus fully described my invention, what I claim as new and desire to secure by Letters Patent is:

1. A bobbin winding mechanism for sewing machines, comprising a supporting member, a spring pressed rocker arm pivoted to the supporting member having bobbin spindle bearings, a bobbin spindle journaled in the bearings having a friction wheel adapted to engage the fly wheel of the machine, a pivoted detent engaging one of the bearings and holding the friction wheel in contact with the fly wheel, and a cast off arm for the detent adapted to be engaged by the thread wound on the bobbin for releasing the detent from the bearing as the winding proceeds. 115

2. A bobbin winding mechanism for sewing machines comprising a supporting member, a spring pressed rocker arm pivoted to the supporting member having bobbin spin-

idle bearings, one of which has a flattened detent engaging surface, a bobbin spindle journaled in the bearings having a friction wheel adapted to engage the fly wheel of the machine, a pivoted detent engaging the flattened surface of the bearing and holding the friction wheel in contact with the fly wheel, and a cast off arm for the detent adapted to be engaged by the thread wound on the bob-

bin for releasing the detent from the flat- 10
ended surface of the bearing as the winding
proceeds.

Toronto, Ontario, October 28th, 1919.

JAMES ALEXANDER FLANAGAN.
